UNITED STATES PATENT OFFICE

2,094,124

DRILLING MECHANISM

Mervin Chester Huffman, Claremont, N. H., assignor to Sullivan Machinery Company, a corporation of Massachusetts

Application August 25, 1933, Serial No. 686,748

7 Claims. (Cl. 255—45)

My invention relates to drilling mechanisms, and more particularly to feeding mechanisms for tower mounted or other drills having a relatively long feeding travel.

5 An object of my invention is to provide an improved drilling mechanism. Another object of my invention is to provide an improved feeding mechanism for a drilling motor. A further object of my invention is to provide an improved 10 feeding mechanism for a drilling motor, providing for a relatively long feeding travel of the drill, and maintaining a minimum over-all height of the drilling apparatus. Still another object of my invention is to provide an improved 15 moving device of particular utility for feeding rock drills, but adapted to provide a very efficient rectilinear feeding movement with a minimum of air or other feeding fluid, for any device requiring reciprocation over substantial distances. 20 Other objects and advantages of my invention will hereinafter more fully appear.

In the accompanying drawings, in which, for purposes of illustration, one embodiment which my invention may assume in practice has been 25 shown,—

Fig. 1 is a side elevation of a drilling apparatus constructed in accordance with one form of my invention.

Fig. 2 is an enlarged vertical section through 30 the feeding mechanism proper of Fig. 1.

Fig. 3 is a transverse section on the line 3—3 of Fig. 1.

Fig. 4 is a detail sectional view through a 35 controlling valve mechanism.

Fig. 5 is a fragmentary sectional view showing a detail of construction.

Referring to the drawings, it will be observed 40 that upon a structural steel tower 1 comprising a plurality of upright frame members 2, there are arranged a top member 3 and an intermediate, structural steel platform structure 4. The platform structure 4 includes a transverse plate member 5 suitably held to the angle irons 6 of frame 4. The top member 3 is also in the form 45 of a plate 10. The plates 5 and 10 are traversed by holes 11 and 12 in which a cylindrical, preferably hollow guide member 13 in the form of a cylindrical tube is secured, as by welding or by a pressed fit, or in any other suitable manner.

50 Parallel to the guide member 13 and also secured within circular openings, in this case numbered 15 and 16, is a vertical feed cylinder 17 having its opposite ends closed by head members 18 and 19. Within the bore 20 of the feed cylinder 17 a piston structure, generally designated

21, is reciprocable. To the piston structure 21 there are connected two of the ends of a pair of flexible cable members 23, 24, whose construction will be more fully described; and these cable members pass respectively over upper and lower sheaves, respectively numbered 25 and 26, and 5 respectively supported on suitable bearing brackets 27 and 28 by means of shafts respectively numbered 29 and 30. The sheaves are arranged with their pitch circles tangent to the line of the 10 axis of the feed cylinder. The guide cylinder 13 and the feed cylinder 17 provide guiding surfaces for a crosshead structure 32, which is herein in the form of a pair of members 33 and 34, each 15 having a curved surface 35 arranged to cooperate with the guide cylinder 13, and another curved surface 36 arranged to cooperate with the feed cylinder 17. The two members are held together by one or more bolts 38 and nuts 39, being properly spaced by shims 40, and adjustable towards 20 and from each other by the removal or addition of shims as desired. Between the outwardly projecting arm portions 41 of the members 33 and 34 is mounted a drilling motor 43, suitably secured by screws 44 to the arms 41 and connected, 25 as at 45, in a manner hereinafter described, with the other ends of the cables 23 and 24.

A suitable air supply line 46, supplied with compressed air or other feeding pressure from any suitable source, branches at 47 and has as 30 one branch an extension 48, which is controlled by a throttle valve 49 and connected by a flexible connection 50 of suitable length with the supply passage of the drilling motor 43. The other branch, 51, is connected to a four-way valve casing 52, in which a four-way valve 53 is rotatably mounted for control by a handle 54. Passages 55 and 56 lead respectively from the top 35 and bottom of the valve casing 52 to the top and bottom end of the feed cylinder 17, and an exhaust connection 57 opens out of the side of the valve casing 52 opposite the communication of 40 the valve casing with the supply branch 51.

The cables 23 and 24 are made of wire rope of 45 suitable strength and flexibility, surrounded by and embedded in a smooth molded rubber cover of circular cross section. A portion of the cable is shown in Fig. 5, the wire rope being indicated at 60 and the molded rubber covering at 61. Fig. 5 is a detail at one end of one of the pieces of 50 cable, and it will be noted that the rubber covering has been carefully removed from a portion of the wire rope 60 and that a metallic sleeve member 62 has been secured to the end of the wire rope. A sound permanent connection can be se- 55

cured by slipping a tubular member over the end of the wire cable and then hammering or swaging the tubular member between suitably shaped dies to cause an embedding of the wires of the cable in the metal of the end connection 62. After this reducing hammering process has been completed, the exterior of the end connection is threaded, as shown at 63.

Referring now to the connection 45 between the outer ends of the cables 23 and 24 and the drilling motor, it will be observed that a block 65 is suitably secured to the drilling motor, and that this block has a longitudinally extending bore 66 in which a sleeve 67, oppositely internally threaded at its opposite ends, as at 68 and 69, is mounted. At one end, the sleeve 67 has a polygonal portion 70 to enable easy turning. The ends of the cables 23 and 24 which cooperate with the internally threaded sleeve member 67 are also oppositely threaded as to their terminal sleeves 62, and each has a lock nut 71 thereon. It is evident that by backing off the lock nuts 71 to the desired distances and rotating the sleeve member 67 by means of the polygonal portion 70, the cables 23 and 24 may be tightened. After the desired tension is obtained, the lock nut 71 may be screwed down and the parts all locked solidly both together and with reference to the board projection 65.

30 The piston structure 21 comprises a central portion 73 having a bore 74 oppositely internally threaded at its opposite ends. It further comprises a pair of bored end members 75, each fitting over one of a pair of cylindrical hollow bosses 76 on the member 73 and each clamping a cupped packing 77 between it and the side of the member 73 which is adjacent to it. Lock nuts 78 cooperate with the threaded portion 73. When assembling the feeding mechanism, the parts of 40 the feed piston can be assembled by rotating the member 73 relative to the threaded ends 62 of the cables 23 and 24, to the desired extent, and the lock nuts 78 may then be screwed down to clamp the several parts of the piston tightly together.

45 Within each of the cylinder heads 18 and 19 there is provided suitable packing means. Obviously, such packing means can assume various forms. In the upper end of the cylinder, within the upper head 19, an ordinary rubber, leather or 50 composition washer 80 is secured, between a shoulder 81 and a suitably bored follower or gland member 82. At the lower end of the cylinder, an inner head member 85 having a hole 86 through the center thereof, is arranged against a shoulder 87. One end of a suitable flexible packing member 88 is clamped between the plate 85 and the head member 18. The other end of the packing member 88 is clamped between a shoulder 89 on the head member and a suitable gland member 55 90. A contractile spring 91 is arranged within the bore 92 of the head member 18 for the purpose of maintaining the packing 88 in sealing relation with the cable.

The mode of operation of the foregoing mechanism will be readily understood. Upon movement of the four-way valve 53 to the position shown in Fig. 4, pressure will flow from the line 46 through branch 81 and through the four-way valve member 53 to the connection 56, and thus to 70 the lower end of the feed cylinder, thereby raising the feed cylinder and lowering the drilling motor. Reversal of the valve 53 will effect opposite movement of the feed piston and raising of the drilling motor. The inactive end of the feed cylinder is 75 vented to exhaust through the connection 57.

By suitable adjustment of the valve any desired control can be effected. Owing to the smooth molded rubber covering upon the cable, fluid tightness is secured at the opposite ends of the feed cylinder. Owing to the employment of a 5 rubber covered wire rope, the necessary flexibility to permit easy passage around the sheaves 25 and 26 is obtained. The use of ordinary wire rope is impossible, by reason of the large loss of air even with the most carefully designed packings. The 10 use of flat bands is unsatisfactory because of packing difficulties. By the use of the flexible, strong wire rope with a smooth cylindrical covering, the combined advantages of fluid tightness such as may be obtained with an ordinary piston 15 rod, and compactness which is impossible with straight piston rods of a length equal to the travel of the feed piston, will be secured. It will therefore be evident that an extremely compact, very 20 efficient feeding mechanism is provided, which is subject to neither of the disadvantages attendant on the prior methods attempted in the effort to solve the problem of a compact and efficient feed mechanism of the character of that disclosed.

While I have in this application specifically described one form which my invention may assume in practice, it will be understood that this form is shown for purposes of illustration, and that the invention may be modified and embodied in various other forms without departing from its spirit 30 or the scope of the appended claims.

What I claim as new and desire to secure by Letters Patent is:—

1. In combination, a guide cylinder, a parallel feed cylinder, a piston reciprocable in said feed cylinder, a guide sheave arranged with its pitch circle tangent to the line of the axis of the feed cylinder and at one end of the feed cylinder, a feed cable connected to said feed piston and extending over said sheave, a crosshead having a 40 portion slidably engaging said cylinders for guidance by the latter, a drilling motor supported by said crosshead at the side of said feed cylinder which is the more remote from said guide cylinder, operative connections between said feed 45 cable and said drilling motor, and means for supplying actuating fluid to said feed cylinder for reciprocating said piston to effect forward and reverse feed of said drilling motor along said parallel cylinders. 50

2. In combination, a guide cylinder, a parallel feed cylinder, a piston reciprocable in said feed cylinder, guide sheaves arranged with their pitch circles tangent to the line of the axis of the feed cylinder and at opposite ends of the feed cylinder 55 respectively, feed cables connected to said piston and extending over said sheaves, a crosshead having a portion slidably engaging said cylinders for guidance by the latter, a drilling motor supported by said crosshead at the side of 60 said feed cylinder which is the more remote from said guide cylinder, operative connections between said feed cables and said drilling motor, and means for supplying actuating fluid to said feed cylinder for reciprocating said piston to effect 65 forward and reverse feed of said drilling motor along said parallel cylinders.

3. In a drilling apparatus, a guide cylinder, a parallel feed cylinder having a feed piston reciprocable therein, a crosshead slidably engaging 70 said cylinders and having a portion extending between said cylinders, a drilling motor supported by said crosshead with its axis in the same plane with the axes of said cylinders but disposed outside the space between the axes of said cylinders, 75

- operative connections between the feed piston and said drilling motor, and means for supplying actuating fluid to said feed cylinder for reciprocating said feed piston to effect forward and reverse feed of said drilling motor along said cylinders. 5
4. In a drilling apparatus, a guide cylinder, a parallel feed cylinder having a feed piston reciprocable therein, a crosshead slidably engaging said cylinders and having a portion extending between said cylinders, a drilling motor supported by said crosshead with its axis in the same plane with the axes of said cylinders but at the opposite side of the feed cylinder from said guide cylinder, operative connections between the feed piston and said drilling motor, and means for supplying actuating fluid to said feed cylinder for reciprocating said feed piston to effect forward and reverse feed of said drilling motor along said cylinders. 10
5. In combination, a guide cylinder, a parallel feed cylinder, a piston reciprocable in said feed cylinder, a guide sheave arranged with its pitch circle tangent to the line of the axis of the feed cylinder and at one end of the feed cylinder, a feed cable connected to said feed piston and extending over said sheave, a crosshead having a portion slidably engaging said cylinders for guidance by the latter, a drilling motor supported by said crosshead at the side of said feed cylinder which is the more remote from said guide cylinder, the longitudinal axes of said cylinders and the drilling motor lying in a common plane, operative connections between said feed cables and said drilling motor, and means for supplying actuating fluid to said feed cylinder for reciprocating said piston to effect forward and reverse feed of said drilling motor along said parallel cylinders. 15
6. In combination, a guide cylinder, a parallel feed cylinder, a piston reciprocable in said feed cylinder, guide sheaves arranged with their pitch circles tangent to the line of the axis of the feed cylinder and at opposite ends of the feed cylinder respectively, feed cables connected to said piston and extending over said sheaves, a crosshead having a portion slidably engaging said cylinders for guidance by the latter, a drilling motor supported by said crosshead at the side of said feed cylinder which is the more remote from said guide cylinder, the longitudinal axes of said cylinders and the drilling motor lying in a common plane, operative connections between said feed cables and said drilling motor, and means for supplying actuating fluid to said feed cylinder for reciprocating said piston to effect forward and reverse feed of said drilling motor along said parallel cylinders. 20
7. In a rock drill, a frame having end supports, parallel guide and feed cylinders mounted at their ends on said end supports, a feed piston reciprocable in said feed cylinder, a sliding crosshead guided by said parallel cylinders, a drilling motor mounted on said crosshead, the longitudinal axes of said feed and guide cylinders and drilling motor lying in a common plane, connections between the opposite ends of said feed piston and said crosshead, and means for supplying actuating fluid to said feed cylinder for reciprocating said feed piston to effect forward and reverse feed of said crosshead and drilling motor along said parallel cylinders. 25
